UNITED STATES PATENT OFFICE.

HARLEY W. POWELL, OF OAKLAND, CALIFORNIA.

QUICK-OPENING VALVE.

Application filed July 5, 1924. Serial No. 724,261.

To all whom it may concern:

Be it known that I, HARLEY W. POWELL, a citizen of the United States, residing at Oakland, in the county of Alameda and 5 State of California, have invented certain new and useful Improvements in Quick-Opening Valves, of which the following is a specification.

My invention relates broadly to valves, 10 and more particularly to that type of valve adapted for quick opening.

In commercial laundries and the like places where a great deal of water is used intermittently throughout the day, it is very 15 important as a time-saving factor to employ valves that can be opened and closed in the least time and with the least effort to maximum open and closed positions, so that the filling of tubs, washing machines and other 20 washing apparatus may be accomplished with a quick-flooding, so to speak.

As laundries use large volumes of water, they are generally supplied with the same 25 from their own wells, and which water is stored in elevated tanks, and of course by reason of such storage means, the water is supplied to the piping system under comparatively low pressure. This then necessitates a quick-opening valve for efficient re- 30 sults throughout the laundry, as one man may be taking care of a dozen washing machines, so it is evident such an operator needs equipment of the character of my invention. Furthermore, because of the constant opera- 35 tion of the valves, it is essential that they be very durable and free from the necessity of frequent regrinding.

Therefore, from the above, the two major 40 objects of my invention are to produce a quick-opening valve for immediate flooding, and designed to substantially eliminate valve-regrinding.

Another object is to house the valve parts in a simple and shallow cylindrical casing, 45 adapting the cover for the casing to carry the said parts for accessibility to the interior of the valve when the cover is removed and without disturbing the piping system in the least.

50 A further object is to construct the valve with two ports, each port covered with a valve thus insuring a double-seal against leakage.

A still further object is to construct the 55 cover with stops to limit the valve-operating movement to substantially a 90-degree turn,

and permit the casing to be free of obstructions for ease in boring the same.

I will now describe an exemplifying construction in which the invention is embodied. 60 This is the best form that I have devised up to the present time, but it should be understood that the invention is capable of embodiment in other forms.

In the drawings: Figure 1 is a plan of 65 the valve, with about one-half of the cover broken away to show parts of the interior; also a portion of the casing is broken away to show the outlet port in cross-section.

Fig. 2 is a vertical diametrical section of 70 certain parts to illustrate in detail the invention; other parts are shown in full lines.

Adverting to the drawings: The numeral 3 designates the casing of my invention, and which is preferably a cylindrical casting of 75 shallow depth and having an open end 4 and a closed end 5. The casing is bored as at 6 and may have cast or machined counterbores 7 and 8. In the side of the casing are tapped ports 9 and 10, here shown diametrically opposed though they need not be in every case. 11 is the inlet pipe and 12 the outlet, by reason of the fact that one generally turns the valve-lever counter-clockwise to open the valve. 80

To the open end 4 of the casing I secure 85 a cover 13 as by machine screws 14 or other suitable means, with a gasket 15 therebetween, if desired, for sealing purposes. To the inside central portion of both the 90 cover 13 and the closed end 5, are formed bosses 16 of equal depth for a purpose to be later described. On the outside of the cover is a threaded boss 17, to receive the usual stuffing-box gland 18 enveloping any suitable packing 19, and compressing the same 95 about the valve stem 20. 21 is a lever-handle mounted on the end 22 of the stem and secured thereto as by set-screw 23, Fig. 1. 100

Between the heretofore mentioned bosses 16 is positioned the symmetrically formed valve means, comprising a rod-member having arms 24 radiating from a body 25. Each arm freely supports duplicate valves 26 and 26' having cylindrical peripheral surfaces 27 in register with the bore 6, and of size to sufficiently cover the ports 9 and 10. Each valve has a boss 28 extending inwardly having a central hole 29 deep enough to 110 provide a clearance space 30 at the end of each arm 24.

Interposed between each valve boss 28 and the body 25 and encircling the arm is a coil-spring 31, compressed to a desired degree to outwardly hold the valves 26 and 26' in tension against the bore 6 for valve-seating purposes. At the base of each valve boss 28 is a series of holes 32, to admit water to the clearance space 30 to effect the utilization of the water pressure in the casing on the valve area thereat. After the valve means is properly positioned in the casing with respect to the ports and the counter-bores and the valve stem 20, the set-screw 33 through the body 25 effects a securing of the said valve means as a unit on the stem 20.

On the underside of the cover 13 are cast a pair of stops 34 and 35 and so positioned as to limit the angular movement of the valves. In Fig. 1 the ports are shown closed, the valve 26' bearing against the stop 35; and when the handle 21 is moved to the dot-and-dash position, the ports will be open and the valve 26 will abut against the stop 34.

In operation, the head of water at the inlet will exert some pressure on the valve surface 27 and tend to press the valve inwardly, but the coil-spring 31 can be made strong enough to more than overcome the pressure head. Thus, it will be observed that if the handle 21 is moved through an arc of 90 degrees, or even much less if desired, both valves will be unseated and the full flow of water effected; and on reversing the handle, double sealing will be effected against leakage of water through the outlet, and the trapped water in the casing will exert its pressure in all directions equally and will further tend to seat the valves in conjunction with the coil-springs 31.

While I have thus described the preferred form of my invention, I wish to have it understood that changes may be made

within the scope of the claims hereto attached without affecting the spirit of the invention, therefore, what I claim as new and desire to secure by Letters Patent of the United States, is the following:

1. A quick-opening valve of the class described, comprising a cylindrical casing of relatively large bore and shallow depth, the casing provided with opposed inlet and outlet ports, a valve for each port having a continuous valve-seat face for cooperating with the cylindrical casing, the casing provided with a closed bottom and open top, a cover for the casing, a central inwardly projecting boss formed on said cover and another boss on said casing bottom, a valve stem supported in said bosses, a solid transverse rod spaced midway in said casing between said bosses and secured on said stem, said valves having inwardly projecting bosses of equal depth, each boss bored to receive an extremity of the transverse rod, said rod having shoulders formed thereon equidistant from its center, a pair of coil springs concentrically mounted one on each end of said rod and between said shoulder and valve boss, and each of said springs adapted to hold the valve in seating engagement with the casing bore, and the said cover provided with stops to limit the angular movement of the transverse rod for the quick opening of the valve.

2. A structure as set forth in claim 1, and in which each valve boss has a bore of greater depth than the portion of the transverse rod received therein, and each valve boss provided with an additional bore leading to the interior of the casing to effect the utilization of the full water pressure on the valve and to provide a floating connection for the valve on the rod.

In testimony whereof I affix my signature.

HARLEY W. POWELL.
